UNITED STATES PATENT OFFICE

2,506,359

WELL BLOWOUT PREVENTER

William E. Haslam, Burbank, Calif., assignor of
forty-nine per cent to Karl M. Brenner, Long
Beach, Calif.

Application March 1, 1946, Serial No. 651,136

1 Claim. (Cl. 286—26)

1 My present invention relates to an improvement in well blowout preventers and more particularly to a hydraulic pressure control apparatus adapted to be placed in operation at the first sign of high pressure in the well.

The principal object of my invention is to provide an improved hydraulically actuated apparatus for controlling a well, whereby the bore of the well may be sealed when high pressures are encountered.

A particular object of the invention is to provide an improved apparatus for controlling a well which is so constructed that the bore of the well may be packed off when a pipe or tool is extending therethrough in order to prevent blow-outs of said well due to high pressures.

The result of the use of said apparatus will be that the well may be kept under control under all operating conditions; the apparatus being actuated by hydraulic means whereby operation thereof may be quickly and easily accomplished.

Another object of the invention is to provide an improved well control apparatus which includes a hydraulically operated blow-out preventer for packing off around a pipe or tool extending through the well bore.

The blow-out preventer consists of an inflatable, flexible member having an axial bore of sufficient diameter to accommodate drill pipe and well tools and having a common inlet and outlet for admitting and discharging fluid under pressure, whereby the member may be expanded into sealing engagement with the pipe or tools to pack off the bore of the blow-out preventer whenever there is a possibility of a blow-out; said member permitting normal operations when in its normal deflated position.

The blow-out preventer consists of a tubular member made of rubber, or other resilient material, coiled helically within the bore of a cylindrical housing and being arranged to be inflated so as to pack off around the pipe or tool extending through said bore; the helical arrangement of the member permitting a slight leakage of pressure upwardly through the spiral aperture for lubrication and pressure indication purposes.

In the drawings I have illustrated one complete example of the physical embodiment of my invention according to the best mode I have thus far devised but it will be understood that changes and alterations may be made in the exemplified structure within the scope of the appended claim.

In the drawings:

2 Figure 1 is an assembly view of the blow-out preventer in position to operate.

5 Figure 2 is a sectional view of the three-way valve in position to introduce pressure into the hose.

Figure 3 is a sectional view of the three-way valve in position to hold pressure within the hose.

10 Figure 4 is a sectional view of the three-way valve in position to discharge pressure from the hose.

Figure 5 is a top plan view of the blow-out preventer showing the hose inflated against the drill pipe and the rupture preventing paddles in effect.

15 Figure 6 is a vertical sectional view of the housing showing the hose expanded against the drill pipe and rupture paddles in effect.

Figure 7 is a vertical sectional view of the housing showing the blow-out hose deflated and in receded position from the pipe.

20 Figure 8 is a detail view of the hose partially broken away.

Figure 9 is an enlarged detail view of a section of the top part of the housing with the rupture 25 preventing paddles in position.

Figure 10 is also an enlarged detail view of the paddles taken through the top part of the housing at right angles to the cutting plane of Figure 9, in which the paddle is viewed from the right of Figure 9.

30 Referring now to the assembly view, the usual drill pipe is shown at 5 and surrounded by the casing nipple 8. On the side of the casing nipple I have shown a normal or usual main closure gate 9 through which the oil and gases pass.

35 Below the main closure gate I have illustrated a conventional landing head 10 for the casing 6 supported upon the floor 12 of the cellar.

Above the casing nipple 8 I mount a flange 2 40 supporting the blow-out preventer barrel or housing 1.

The usual derrick floor 7 carries the rotary table 6.

45 Within the housing 1 is located the blow-out preventer comprising preferably a rubber hose 18 spirally wound within the housing around the drill pipe from bottom to top. This rubber hose in deflated condition forms a helical aperture within the housing through which a slight leakage of pressure is permitted.

Exteriorly of the housing 1 I utilize an attaching flange 19 connecting within the housing with the hose, and exteriorly the flange connects with the pipe 3a leading to the three-way valve 55 3. A pressure discharge pipe line 3b permits the

release of pressure when desired. A valve control wheel 4 is adapted for manual operation when high pressure within the well is indicated. A valve core 13 provides for the direction of flow of the fluid under pressure.

At spaced intervals above the spiraled hose and on the housing I employ rupture preventers for the hose comprising paddles 14 releasably pressing the hose by means of springs 15 and secured to the housing by bolts 16. With respect to these paddles, it may be noted from Figures 9 and 10 that each paddle is pivotally mounted on bolts 16, and that extending around each pivotal connection is a spring 15 one end of which engages under the inclined flange formed on the top part of the housing and against which the paddle is swung upwardly in Figure 9, the other end of the spring being passed around the pivotal connection and being in engagement with a side lug formed on the medial portion of the paddle. Thus, the tendency of the spring is to force the paddle 14 normally downwardly away from said flange of the housing, the paddle being swung upwardly against said flange upon inflation of the hose.

The design of the invention is such that it is possible to raise, lower or rotate drill pipe not only when the blowout preventer is in a deflated condition, but also when it is inflated or expanded by hydraulic pressure, so as to control pressure from within the well. This feature is very important in well drilling operations.

It will be noted, also, that the area of contact between the well blowout preventer and the drill pipe or other surface with which it is engaged when expanded, is greatly increased over the known devices. In other words, a more effective seal against internal pressure is obtained by increasing the area of contact where a blowout might occur. This feature also permits less pressure within the preventer than would otherwise be necessary. For example, tests have shown that it is possible to pack off or control pressure within the blowout preventer of only 1,500 pounds, whereas with conventional means a pressure within the blowout preventer of up to 10,000 pounds would be required to accomplish the same thing.

Another advantage resides in the fact that the blowout preventer is coiled in the same direction in which the drill pipe turns. Thus, when the blowout preventer is being used, the motion of the drill pipe tends to tighten and maintain the pressure of the blowout preventer rather than to roll down and loosen the bearing surfaces, as occurs in other devices. This feature also contributes to the ability of the device to control

pressures within the well with a comparatively low pressure within the blowout preventer.

From the above description of the parts of my invention it should be apparent that when high pressure within the well is indicated, the operator will turn the valve 3 to position illustrated in Figure 2 whereupon the hose will be inflated and will completely seal off the space within the housing surrounding the drill pipe.

When the danger is past the valve will be turned from the position of Figure 3 to the position of Figure 4 releasing the pressure from the hose and deflating it.

By the utilization of my invention, serious dangers and wasteful blow-outs will be prevented, and the device simple in construction and durable may be attached to any existing type of well construction.

Having thus fully described my invention, what I claim as new and desire to secure by Letters Patent is:

In a blow-out preventer for a drilled well, a housing adapted to surround the drill pipe of said well, the upper end of the housing being flanged inwardly and inclined downwardly toward the pipe, a flexible hose wound spirally around the pipe and having its upper end closed, the lower end of the hose being open, means anchoring the lower end immovably to the lower end of the housing, said lower end constituting a common inlet and outlet, paddles pivotally connected to the upper end of the housing, springs on the paddles yieldably pressing the paddles against the hose, said paddles underlying the inclined flange of the housing and overlying the hose, whereby on inflation of the hose said paddles will prevent rupture thereof, said flange being adapted to provide a stop for the paddles whereby to relieve the pivoted connections of the paddles of strain imposed thereon.

WILLIAM E. HASLAM.
